United States Patent

Des. 237,132
Patented Oct. 14, 1975

237,132

DRAWER SLIDE OR SIMILAR ARTICLE

Martin O. Riley, 1330 Hillcrest Ave.,
Pasadena, Calif. 91106

Filed Aug. 30, 1973, Ser. No. 393,011

Term of patent 14 years

Int. Cl. D6—06

U.S. Cl. D6—191

FIG. 1 is a rear top perspective view of a drawer slide or similar article showing my new design;

FIG. 2 is a side elevation view thereof;

FIG. 3 is a bottom view thereof; and

FIG. 4 is an enlarged fragmentary view of the slide in perspective and disclosing certain features thereof in greater detail.

I claim:

The ornamental design for a drawer slide or similar article, as shown.
